UNITED STATES PATENT OFFICE.

FRANK A. PETERS, OF CHICAGO, ILLINOIS.

DRAFFERY SUPPORT.

Application filed May 28, 1920. Serial No. 384,870.

To all whom it may concern:

Be it known that I, FRANK A. PETERS, a citizen of the United States, and a resident of the city of Chicago, in the county of Cook and State of Illinois, have invented certain new and useful Improvements in a Drapery Support; and I do hereby declare that the following is a full, clear, and exact description of the same, reference being had to the accompanying drawings, and to the numerals of reference marked thereon, which form a part of this specification.

This invention relates to curtain and drapery supports and is particularly adapted for use with window curtains and the like. The subject of this invention constitutes improvements upon a prior patent granted to me, No. 1,327,961, issued January 13, 1920, and this application is also a companion to my copending case Serial No. 381,324, filed May 14th, 1920.

Hitherto in washing or cleaning windows it has been necessary to either remove the curtains therefrom or support them in some manner, thereby running the risk of damaging or rumpling same.

Also, in changing curtains, it has heretofore been necessary to ascend a stepladder which was accompanied with more or less danger and trouble.

One of the principal objects of this invention is to provide means whereby window curtains can be replaced without the use of a ladder.

Another object of the invention is to provide a method of supporting the curtains while cleaning the windows, so as not to interfere with the work of cleaning and also so that the curtains will not be soiled.

Still another object of this invention is to provide means whereby free access may be had to the window for any purpose without disarranging or rumpling the curtains.

A further object of this invention is to provide means whereby the window may be opened at any time for purposes of ventilation without danger of snow, soot or the like blowing upon the curtains.

Still another object of the invention is to provide a hanger for the curtains which has means for partly lowering the same to admit air and light, said means being ordinarily invisible and out of the way.

Other and further important objects of this invention will be apparent from the disclosures in the specification and drawings.

The invention (in a preferred form) is illustrated in the drawings and hereinafter more fully described.

On the drawings:

Figure 1 is an elevation of a window frame having a curtain and draperies supported thereon by my improved device.

Figure 2 is a similar view with the curtains removed.

Figure 3 is an elevation of the main portions of the hanger and the adjusting devices, parts being broken away.

Figure 4 is a top plan view of the horizontal portion of the bracket.

Figure 5 is a section taken on the line 5—5 of Figure 3.

Figure 6 is a section taken on the line 6—6 of Figure 3, showing the connection between the horizontal and vertical elements.

Figure 7 is a section taken on the line 7—7 of Figure 4.

Figures 8, 9 and 10 are different views of a modification of the connection shown in Figure 6.

As shown on the drawings:

The drapery support comprises two main portions, a vertical tube 12 and a horizontal member 14. The vertical tube 12 has inserted into its lower end a rod 16 held fixed therein by a pin 18. On the end of the rod 16 is pivoted at 20 a handle 22. The pivot consists of a slot and tongue connection, as shown, the purpose of which is hereinafter described.

Inside the tube 12 and fitted slidably therein is a rod 24 formed in an offset plate 26 at its upper end, the plate 26 being fastened to the upper right hand corner of the frame by screws 28. The rod 24 is of such a length as to extend to a bracket 30 fixed to the window frame by means of screws 32 at a point approximately one-third of the height of the frame. The tube 12 is slideable on the rod 24 and is held in adjusted position in the bracket 30 by means of a coiled spring 34 and a wedge lever 36 coacting therewith. The wedge lever 36 is provided with an opening through which the tube 12 passes and it is supported at its in-

ner end upon a projection 38 formed in the back of the bracket.

At its upper end the tube 12 has brazed or otherwise fixed thereto a supporting member 40 of the shape shown in Figure 6. This member 40 has firmly secured to it in any suitable manner at 42 the horizontal member 14. The member 14 may be soldered or brazed thereto and a pin 44 passed therethrough to help retain it in position or the horizontal member may be attached to the vertical tube in the manner shown in Figures 8, 9 and 10. The end of the horizontal tube or rod is flattened and then bent back and down at 46 in the manner shown and finally twisted through ninety degrees and brought around the vertical tube as at 48 to be riveted in position. In this way the horizontal member is fixed to the vertical tube member to move therewith. The horizontal member is preferably made in two parallel telescoping sections. As shown in Figure 4, the main drapery support consists of a rod 50 and a tube 52 with the rod 50 slidable therein. An auxiliary curtain support consists of the tube 54 and rod 56, which are telescopic and removable from the main portion of the device. The end of the rod 50 is bent back toward the window and is shaped in the manner shown at 58 in Figure 7. This end is adapted to fit into a spring clip 60 fastened to the upper left hand corner of the window frame. The end 58 of the rod 50 may be readily detached from the spring clip 60 by a slight pull, but is sufficiently held thereby so as not to be displaced accidentally, as by a gust of wind or the like.

The operation is as follows:

Whenever, for any reason, free access to the window is desired, as when it is to be cleaned, or fully opened to admit air, especially in the case of French windows, the curtains can be entirely removed from their normal position in the window, by grasping the handle 22, swinging same to a horizontal position and then turning it back so that the end of the bar 58 is pulled from the spring clip 60 and the horizontal curtain support with the curtains thereon is swung back in the manner of a door, thereby leaving the window entirely free and unobstructed. The wedge lever 36 holds the vertical tube against any downward movement but admits of its free turning in a horizontal plane about its longitudinal axis.

Whenever it is desired to replace the curtains, the curtain supporting member may be lowered to a convenient level, as shown by the dotted lines in Figure 2, by first disengaging the end 58 of the bar 50 from the spring clip 60 in the manner just described and then the entire support may be lowered by pushing the wedge lever 36 upward against the tension of the spring 34,

thereby permitting a free vertical movement of the tube 12, which may be then held in any adjusted position by releasing the wedge lever 36. It will be seen that the curtains can be lowered to such position at any time when it is desired that light or air be admitted at the top of the window.

This invention provides a compact and entirely unnoticeable means of affording free access to the window at all times and a ready method of changing the curtains without danger of falling and also a convenient means of admitting air and light from the top of the window without disarranging or removing the curtains. The horizontal member is made in telescoping sections so that it may be adjusted to any width of window and any convenient means of retaining same in adjusted position may be used, as set screws or the like.

I am aware that numerous details of construction may be varied through a wide range without departing from the principles of this invention, and I therefore do not purpose limiting the patent granted otherwise than necessitated by the prior art.

I claim as my invention:

1. A device of the kind described comprising a frame, a vertical rod secured to the frame, a vertical tube slidable and rotatable on the rod, a horizontal curtain supporting member carried by the tube, and means for releasably clamping the tube against vertical movement but allowing of its free rotation in a horizontal plane.

2. A device of the kind described comprising a frame, a vertical rod secured at its upper end to the frame, a tube slidable and rotatable on the vertical rod, a bracket fixed to the frame and means in the bracket for releasably holding the tube from longitudinal movement, and a horizontal curtain supporting member carried by the tube.

3. A device of the kind described comprising a frame, a vertical rod secured at its upper end to the frame, a tube slidable and rotatable on the vertical rod, a bracket fixed to the frame and means in the bracket for releasably holding the tube from longitudinal movement, a pivoted operating handle fixed to the lower end of the tube, and a horizontal curtain supporting member carried by the tube.

4. In a device of the class described, a rod, a fastening securing the upper end of said rod, a tube slidably mounted on said rod, a support vertically below said fastening and guiding said tube, whereby said rod is maintained vertical, said support releasably holding said tube from vertical movement but permitting rotation thereof, and means secured to the lower end of the tube to facilitate rotation thereof.

5. In a device of the class described, a rod, a fastening securing the upper end of said

rod, a tube slidably mounted on said rod, a casing vertically below said fastening, said casing surrounding said tube, whereby said rod is maintained vertical, and clamp-
5 ing means within said casing releasably holding said tube from vertical movement but permitting rotative movement thereof.

In testimony whereof I have hereunto subscribed my name in the presence of two subscribing witnesses.

FRANK A. PETERS.
